TUMBLER BASKET FOR COLLECTIVE
DISHWASHING

Catherine Barrie, Cold Spring Harbor, N. Y.

Application November 16, 1937, Serial No. 174,793

11 Claims.

(Cl. 141—9)

This invention relates to devices for the collective washing of tumblers and the like.

The present application illustrates a form of a device for the collective washing of dishes, as by manual operation, and especially where the dishes may be stored in the device, to be removed therefrom only when required for use. More specifically, the invention relates to the collective washing of dishes, as set forth, and wherein the device with the washed or rinsed dishes therein, may be inverted to cause drainage and air drying of the dishes, as originally placed in the device, so that the latter may be put in a closet or the like for subsequent use, without requiring any intermediate handling of the dishes. Other specific forms of the broad invention are disclosed in my patent applications filed herewith entitled Plate basket and basin for collective dish washing, Serial No. 174,797, and Cup and saucer basket for collective dish washing, Serial No. 174,794, the latter application being a particularly good illustration of a modified form of the present invention.

One object of the invention is to provide improved means and methods for accomplishing the results and advantages above stated.

Another object of the invention is to provide an improved device of the character described adapted for the safe handling of tumblers.

Another object of the invention is to furnish a device of the nature set forth adapted to hold and lock in position tumblers of different sizes, in an improved manner, for the purpose specified.

A further object of the invention is the provision of an improved device of the type mentioned having few and simple parts, and which is inexpensive to manufacture, convenient, durable, reliable and efficient in use; and also improved methods of practising the principles of the invention.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a plan view of the invention, with the closure in locked position, and an open position thereof being in part indicated in dot-dash

lines; and tumblers therein being shown in dot-dash lines.

Fig. 2 is a view in elevation thereof.

Fig. 3 is a sectional view taken on the line 3—3 of Fig. 1, with a tumbler shown in dot-dash lines.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a device embodying the invention. The same may include a container of foraminous or reticulated material, such as a wire basket, the wires 20 of which are suitably soldered, welded or otherwise interconnected. Coating with or forming a part of the basket is a closure means 12, which is closable and operable, as, for instance, by relative angular motion between the basket and the closure means, or by relative motion between portions of the closure means and the basket. For example, tumblers or other dishes 13 are disposed in upright spaced compact relation within suitable openings or holder sections such as 14, the closure means serving to cause the tumblers to be thus retained even when the basket is inverted for draining the rinsing water from the tumblers. The device 10 affords sufficiently large openings for adequate and free rinsing and washing of the tumblers, as with an insertable mop, and for free drainage and air circulation for rapid drying of the tumblers. It may be noted that by the word tumbler as herein used, may be denoted any dish which is to be washed such as plates, cups, and the like, and not merely drinking glasses. It will be observed that the operator need not insert her hands in dish water to wash the dishes.

The basket 10 may include three coaxial vertically spaced wire rings 15, 16, and 17 of like diameter. Disposed in spaced coaxial relation thereunder is a fourth wire ring 18 of substantially smaller diameter than the rings 15, 16, and 17.

Interconnecting the rings 15, 16, 17 and 18 are equally angularly spaced like upright wire elements 19, each being bent at the ring 17 to provide an inward downward extending portion 19a to suit the diameter of the base ring 18. From

- the latter, the wires 19 may have integral inward extending radial portions 19b all of which lie in a common plane. At a suitable point such as 19c, the wires 19 have upright portions 19d which 5 may extend up to the plane of the ring 15, these parts 19d defining an inner cylindrical region coaxial with the rings 15 to 18. At the upper ends of the wire portions or stays 19d, is secured an inner ring 20 which lies coaxially substantial- 10 ly in the plane of the outer rim ring 15. Also secured to the stays 19d is an inner ring 21 which lies coaxially substantially in the plane of the outer ring 16. If desired, the inner rings 20, 21 may lie somewhat below the planes of their respective outer rings 15 and 16.
- To radially divide the device for receiving six tumblers, wire elements 17a may extend radially at equal angles to connect the wire 11 with the wire 19d or with any other suitable part.
- For reliably holding the tumblers, there may be disposed coaxially in the plane of the outer ring 18, an inner wire ring 22, secured to the radial wire portions 19b and carrying or having integrally formed therefrom a series of equally angularly spaced holder portions 23. These are arranged so as to be angularly offset relative to the stay wires 19 for a purpose that will be hereinafter apparent. Each holder portion 23 may have an inwardly offset tumbler supporting portion 23a which lies radially in the plane of the outer ring 18, and an upstanding portion 23b that may be somewhat larger than the parts 23a. The arrangement may be such that the parts 23a, 23b form a loop integral with the ring 22.
- In use, a tumbler 14 is inserted through the top of the basket as shown in dot dash lines in Figs. 1 and 3. The tumbler thus rests upon the outer ring 18, which was made of reduced diameter for this purpose, and upon the portion 23a of a holder 23. One or both of the outer rings 16, 17 form an outer lateral support for the tumbler. If the tumbler is of sufficient height to reach the ring 15, the latter may also form an outer lateral support therefor. The upright portion 23b of the holder 23 acts like a resilient clip to exert an outward lateral pressure on the tumbler and thus cause the same to be reliably held. One or both of the inner rings may laterally abut the tumbler to afford an inner support 45 therefor. Six tumblers may be thus mounted.
- In order to reliably retain the tumblers as in the event that the device 10 is inverted to drain water from the tumblers, and also to thus co-operate with tumblers of different heights, the closure means 12 may be mounted for vertical as well as angular movability, as between the rings 15, 16. More specifically, the closure means 12 may include a wire ring 24 which may be of substantially like diameter with the inner rings 50 20, 21. Extending from the ring 24 at equally angularly spaced points are the radial wire elements or bars 24a, which terminate in the loop or hook like inwardly bent portions 24b. The parts 24, 24a and 24b may lie in a common plane 55 intermediate of the rings 15, 16. Since the bars 24a project beyond the rings 15, 16, accidental removal of the closure means 12 is avoided.
- Coacting with the bars 24a or their anchor portions 24b, are a series of equally angularly spaced hooks 25 secured on the ring 16 in up- 60 standing relation and all opening in one direction, so that the parts 24b may be simultaneously engaged with or released from the hooks 25 upon angular movement of the closure means 12 in one 65 or an opposite direction, and with the bars 24a

resting on the ring 16. This mode of engagement is used where the tumblers reach only up to the ring 16, the bars 24a then diametrically closely overlying the respective tumblers to prevent removal thereof. If the tumblers are of the greater length so as to reach the ring 15, the bars 24a will merely upwardly rest against the ring 15, and the hooks 25 will not be utilized.

To prevent accidental reverse angular movement of the closure means 12 and hence unintended release of the tumblers, a suitable locking means 26 may be provided. The same may include coplanar diametral wire rails 26a, 26b secured at their ends to the respective inner rings 20, 21 and lying in the planes thereof. These rails 26a, 26b may carry a pair of small slide rings 26c, 26d, respectively. The locking means 26 may also comprise short alined diametrically disposed wire elements 24c, which terminate in spaced relation to each other, and may form integral extensions of a pair of the bars 24a. In the locked position of Fig. 1, the lower lock rings 26d have been outwardly slid along the rail 26b to engage around the closure elements 24c, and thus to prevent angular movement of the closure 25 means 12. If the latter be elevated for the larger tumblers, then the said closure elements 24c may be locked in like manner by the upper lock rings 26c. It may be noted that the ends of the closure elements 24c have been shown inwardly bent on 30 themselves to provide blunt ends and reliable frictional engagement with the lock rings 24c and 24d.

To remove the tumblers, the lock rings 26c or 26d, as the case may be, are moved toward 35 each other to release the closure elements 24c, and hence to permit the closure means 12 to be rotated to the position suggested in dot-dash lines in Fig. 1, so that the bars 24a lie laterally of the tumblers and permit the free removal of 40 the latter. Angular movement of the closure means is limited by the adjacent stay wires 19. By suitably overlying the tumblers, the closure means 12 coacts with the basket 11, or with frame portions such as 23, or both, to cause the tumblers 45 to be held against accidental slipping from predetermined position.

It will thus be seen that I have provided a device which fulfills the objects of the invention and is well adapted for practical use. The tumblers may be readily rinsed or washed while disposed in the device 10, then inverted with said device for draining and drying, and then stored away for later use, as originally placed in the device and without further handling.

I claim:

1. A device including a reticulated means for receiving and holding dishes and affording substantial openings for the washing and air drying of the dishes therein through said openings, comprising a container consisting of a material which will not be substantially affected by repeated and prolonged exposure to water, said container having means therein for holding a series of dishes in spaced predetermined relation to each other 60 and with the concavities of the dishes facing upward, closure means for the container permanently connected with the latter to assure reliable retention of the dishes in the relation mentioned upon inverting the container to cause 70 draining and air drying of the dishes, said closure means being movable to raised and lowered positions and being horizontally movable in each of said positions to operative and inoperative positions, and means for releasably securing the 75

- closure means in raised and lowered operative positions.
2. A device according to claim 1, wherein the closure means is skeletonized to provide a frame so related to the dish holding means as to clear the latter and to overlie the latter in open and closed positions of the closure means, for the respective removal and retention of the dishes and said closure means being movable about a vertical axis to said operative and inoperative positions.
3. A device including a reticulated means for receiving and holding dishes and affording substantial openings for the washing and air drying of the dishes therein through said openings, comprising a container consisting of a material which will not be substantially affected by repeated and prolonged exposure to water, said container having means therein for holding a series of dishes in spaced predetermined relation to each other and with the concavities of the dishes facing upward, and closure means for the container coacting with the latter to assure reliable retention of the dishes in the relation mentioned upon inverting the container to cause draining and air drying of the dishes, the dish holding means being arranged about a central point, and the closure means being mounted for angular movement about an axis coincident with said center point, the closure means having openings and intermediate bars, said openings and said bars selectively registering with the dish holding means according to the position to which the closure means has been moved.
4. A device including a reticulated means for receiving and holding dishes and affording substantial openings for the washing and air drying of the dishes therein through said openings, comprising a container consisting of a material which will not be substantially affected by repeated and prolonged exposure to water, said container having means therein for holding a series of dishes in spaced predetermined relation to each other and with the concavities of the dishes facing upward, and closure means for the container coacting with the latter to assure reliable retention of the dishes in the relation mentioned upon inverting the container to cause draining and air drying of the dishes, the dish holding means and the closure means being arranged about a common axis, and locking means being provided to control the action of the closure means, said locking means being operative in part by relative angular movement between the container and closure means.
5. A device according to claim 1, wherein the container comprises a wall having a pair of spaced coaxial outer rings, a pair of spaced coaxial inner rings coaxial with and lying along the planes of the outer rings, the closure means being coaxial with said rings and being movable up and down between the upper and lower inner and outer rings, the means for releasably holding the closure means including means for holding the closure means in engagement with the lower outer ring.
6. A device including a reticulated means for receiving and holding dishes and affording substantial openings for the washing and air drying of the dishes therein through said openings, comprising a container consisting of a material which will not be substantially affected by repeated and prolonged exposure to water, said container having means therein for holding a series of dishes in spaced predetermined relation to each other, and a reticulated closure means movable to operative and inoperative position to overlie and clear the dish holding means, said closure means and dish holding means being arranged about a vertical axis, and the closure means being mounted for movement about said axis to said operative and inoperative positions.
7. A device including a reticulated means for receiving and holding dishes and affording substantial openings for the washing and air drying of the dishes therein through said openings, comprising a container consisting of a material which will not be substantially affected by repeated and prolonged exposure to water, said container having means therein for holding a series of dishes in spaced predetermined relation to each other, and a reticulated closure means movable to operative and inoperative position to overlie and clear the dish holding means, said closure means and dish holding means being arranged about a vertical axis, and the closure means being mounted for movement about said axis to said operative and inoperative positions, said closure means being axially movable to different elevations, and means for releasably securing the closure means in operative position at said different elevations.
8. A device including a reticulated means for receiving and holding dishes and according substantial openings for the washing and air drying of the dishes therein through said openings, comprising a container consisting of a material which will not be substantially affected by repeated and prolonged exposure to water, said container having means therein for holding a series of dishes in spaced predetermined relation to each other, and a reticulated closure means movable to operative and inoperative position to overlie and clear the dish holding means, said closure means and dish holding means being arranged about a vertical axis, and the closure means being mounted for movement about said axis to said operative and inoperative positions, and means for locking the closure means in operative position, the locking means being located wholly in the central axial region of the container.
9. A device according to claim 8, wherein hooks are mounted on the container for securing the closure means according to the direction of movement of the latter, said hooks being located at the outer wall of the container and serving to assume upward pressure on the closure means.
10. A device according to claim 8, wherein the locking means includes diametral wires on the closure and container, and means slidable on one of the wires for releasably engaging the other wire at a plurality of points.
11. A device according to claim 6, wherein certain walls of the dish holding means provide a bearing for the closure means.

CATHERINE BARRE.
